UNITED STATES PATENT OFFICE.

EDWARD B. VERONEE, OF ST. AUGUSTINE, FLORIDA.

FAN ATTACHMENT.

SPECIFICATION forming part of Letters Patent No. 751,963, dated February 9, 1904.

Application filed May 20, 1903. Serial No. 158,019. (No model.)

To all whom it may concern:

Be it known that I, EDWARD B. VERONEE, a citizen of the United States, residing at St. Augustine, in the county of St. John and State 5 of Florida, have invented new and useful Improvements in Fan Attachments, of which the following is a specification.

My invention relates to new and useful improvements in fan attachments; and its object is to provide a device of this character which may be attached to a rocking-chair, cradle, or other article of furniture and which will be operated automatically by the rocking of the furniture.

15 A further object is to provide an attachment of this character which can be readily attached to or removed from position upon a chair or cradle.

With the above and other objects in view 20 the invention consists of a cross-bar in which is slidably mounted a rod having a roller at its lower end. A spring is connected at opposite ends to the rod and bar, so as to hold the roller normally removed from the bar. The rockers 25 of a chair or cradle are adapted to be placed over the ends of the cross-bar, and the upper end of the rod is pivoted to a crank which is arranged at one end of a shaft detachably connected to the top of a chair or cradle. A fan 30 of any suitable form may be attached to the shaft, and when the chair is rocked the crank is reciprocated, thereby imparting an oscillating movement to the fan.

The invention also consists in the further 35 novel construction and combination of parts hereinafter more fully described and claimed, and illustrated in the accompanying drawings, showing the preferred form of my invention, and in which—

40 Figure 1 is a perspective view showing my fan attachment in position upon a rocking-chair, and Fig. 2 is a rear elevation of the cross-bar and lower portion of the rod of the attachment.

45 Referring to the figures by numerals of reference, 1 is a cross-bar having an L-shaped arm 2 at each end, and from the outer ends of these extensions project bow-shaped spring-

arms 3. The rockers 4 of a chair 5 are adapted to be inserted between the extensions 2 50 and the arms 3, and, as is obvious, these arms will clamp the rockers in position at the ends of the bar 1. A bracket 6 is adapted to be fastened to the back of the chair 5 by means of clamping-screws 7, and this bracket has a 55 tubular extension 8 at its upper end, within which is journaled a shaft 9. A crank 10 is secured to the rear end of the shaft and is pivoted to a rod 11, which extends downward through a passage 12 in the cross-bar 1 and is 60 provided at its lower end with a roller or caster 13. A spring 14 is arranged about the rod 11 and is connected at opposite ends to said rod and to the cross-bar 1, respectively. A fan 15 of any desired form has its stem 65 16 arranged within the forward end of the shaft 9, and this stem is adapted to be secured in position in any suitable manner, as by means of a set-screw 17.

When the fan attachment above described 70 has been secured to a chair or cradle, it will be obvious that when the article of furniture is rocked backward the bar 1 and the bracket 6 will be carried downward therewith and the spring 14 will be tensioned. The crank 75 10 will be swung by the rod 11 during the backward movement of the chair, and the fan 15 will therefore be swung to one side. When the chair is rocked forward, tension will be removed from the spring 14 and it will contract, and thereby retain the roller 13 upon the floor and at the same time cause the crank 10 to partly rotate, and thereby swing the fan 15 to the other side. It will be seen that the device is very simple and inexpensive in construction and can be readily attached to a chair. By providing a spring 14 the roller 80 13 is held at all times upon the floor. This roller permits of a slight movement of the rod upon the floor, and any covering upon 85 the floor will not be injured thereby.

In the foregoing description I have shown the preferred form of my invention; but I do not limit myself thereto, as I am aware that modifications may be made therein without 90 departing from the spirit or sacrificing any 95

of the advantages thereof, and I therefore reserve the right to make such changes as fairly fall within the scope of my invention.

Having thus described the invention, what 5 is claimed as new is—

1. A fan attachment for rocking furniture comprising a cross-bar, extensions thereto adapted to receive rockers, means for clamping the rockers within the extensions, a 10 bracket, a shaft journaled therein, a crank at one end of the shaft, a fan at the opposite end, a rod connected to the crank and slidably mounted in the cross-bar, and a spring connecting the rod and bar.

15 2. A fan attachment for rocking furniture comprising a cross-bar, extensions at the ends

thereof adapted to receive rockers, spring-
arms to the extensions for clamping the rock-
ers therein, a bracket, a shaft journaled therein,
a fan adjustably connected to the shaft, a 20
crank connected to the shaft, a rod pivoted to
the crank and slidably mounted within the
cross-bar, a roller at the lower end of the rod,
and a spring upon the rod and connected at
opposite ends thereto and to the bar, respec- 25
tively.

In testimony whereof I affix my signature in
presence of two witnesses.

EDWARD B. VERONEE.
